2 SHEETS—SHEET 2.

UNITED STATES PATENT OFFICE.

ALBERT SIMPSON, OF DRYAD, WASHINGTON.

RESILIENT BEARING FOR WHEELS.

No. 836,656.

Specification of Letters Patent.

Patented Nov. 20, 1906.

Application filed July 11, 1905. Serial No. 269,243.

To all whom it may concern:

Be it known that I, ALBERT SIMPSON, a citizen of the United States, residing at Dryad, in the county of Lewis and State of Washington, have invented certain new and useful improvements in Resilient Bearings for Wheels, of which the following is a specification.

This invention has for its object to provide a resilient or spring bearing for wheels of such a nature as to obviate the necessity for use of the cushion or pneumatic tire of any kind—such as are commonly employed upon the wheels of bicycles, automobiles, and similar vehicles—the invention doing away with the expense incident to the initial cost of such tires and to the wear and tear thereon in practical use.

For a full description of the invention and the merits thereof and also to acquire a knowledge of the details of construction of the means for effecting the result reference is to be had to the following description and accompanying drawings, in which—

Figure 1 is a side elevation of a wheel having the invention applied thereto. Fig. 2 is an enlarged side elevation bringing out more clearly the construction of the invention when applied to the front forks of the bicycle. Fig. 3 is a perspective view of the invention applied to the rear portion of the frame. Fig. 4 is a side elevation of the construction shown in Fig. 3.

Corresponding and like parts are referred to in the following description and indicated in all the views of the drawings by the same reference characters.

In carrying out the invention to show the application thereof the same is illustrated as adapted for use for bicycle-wheels, and in the drawings the numeral 1 designates the frame of the wheel, and the numeral 2 the front forks. To provide a resilient bearing for the wheel at the forks 2, spaced frames 3 are secured to said forks, and each of said frames is formed with a longitudinal guide in the form of a slot 4, the ends of the axle 5 of the wheel being mounted in these guides 4. The rearwardly-extending arm 6 and an extension 7 at the upper and lower portions of the frames 3 are directly secured to the forks 2 by suitable fastenings, such as indicated at 8. A foot 9 is formed at the lower end of each frame 3 and preferably consists of a lateral extension thereof. Mounted in the foot 9 of each frame is a threaded stem 10, passing

therethrough, the upper end of said stem being connected with the lower end of a spring 11, arranged above the foot 9, a nut 12, threaded on the lower extremity of the stem 10 and arranged below the foot 9, being adapted for adjustment, so as to regulate the tension of the spring 11 according to the weight which will be sustained by the wheels when the same are in actual use. A hook 13 connects the upper end of each spring 11 with the axle 5, and it will be seen that when weight is received on the forks 2 the said weight is sustained by the springs 11, as the frames 3 are connected by means of said springs 11 with the axle. The springs 11 and the mounting thereof with reference to adjacent parts thus afford a resilient spring or cushion bearing for the axle, which relieves the frame or support carried by the axle of jar and vibration incident to the travel of the wheel over a surface. The wheel may thus be provided with a solid rim or may be of almost any construction with reference to this part not embodying the use of a rubber tire, the disadvantages of which need no recitation.

In applying the invention supporting the rear of the frame 1 of the bicycle the frames 3^a, which are similar to the frames 3 before described, are used, and said frames 3^a have the guides 4^a and the foot extension 9^a, as hereinbefore described with reference to the frames 3. The springs 11 are mounted on the frames 3^a, which carry the stems 10, adjustable by means of the nuts 12. The hooks 13 at the upper ends of the springs 11 connect said springs to the rear axle 14. The rear portion of the frame 1 of the bicycle is ordinarily provided with the upwardly-inclined slots 15, receiving the axle of the rear wheel, and in this instance transverse bolts 16, connecting the frames 3^a to the rear of the frame 1, are received in the slots 15, establishing connection between the frames 3^a and the frame 1 in a manner which will be readily seen. The usual truing-screws 17, employed to true the axle at the rear of the frame 1, are likewise adapted to engage the connecting member 16 to adjust the same, and thereby admit of truing the wheel, the axle 14 being of course carried in the frames 3^a and admitting of the above, as will be clearly apparent.

It will be understood that the operation of the frames 3^a in relieving the rear portion of the frame 1 or support supported by the rear

wheel of jar and vibration is substantially the same as described with reference to the frames 3. Further, it will be understood that the invention is readily adapted for various kinds of vehicles and to wheels generally, affording a resilient bearing therefor which secures advantages which are important and which have been before mentioned.

Casings 25 will be utilized to surround and house the springs 11 to prevent dirt or other foreign matter from interfering with the proper operation thereof. The casings 25 are shown in section in Figs. 2 and 4 and may be of any suitable form—round, rectangular, or the like—so as to fully answer the purposes in protecting the springs 11.

Having thus described the invention, what is claimed as new is—

1. In a resilient support for vehicles, the combination of a pair of vertically-slotted plates provided at their lower ends with lateral offset portions vertically apertured, an axle mounted in the vertical slots of said plates, a pair of springs, each having a threaded stem at its lower end to pass through the vertical aperture of a lateral extension and provided at its upper end with a hook to engage over an end of the axle, and a

set-nut mounted upon the threaded extension of each stem below the lateral offset 30 through which the said threaded stem passes.

2. In a resilient support for vehicles, the combination of a pair of vertically-slotted plates provided at their lower ends with lateral offset portions vertically apertured, and having rearwardly-extended arms at their upper ends and rear extensions between their ends, means coöperating with the said rear arms and extensions to secure the plates to 40 the frame of the vehicle, an axle mounted in the vertical slots of said plates, a pair of springs, each having a threaded stem at its lower end to pass through the vertical aperture of a lateral extension and provided at its 45 upper end with a hook to engage over an end of the axle, and a set-nut mounted upon the threaded extension of each stem below the lateral offset through which the said threaded stem passes. 50

In testimony whereof I affix my signature in presence of two witnesses.

ALBERT SIMPSON. [L. S.]
